CLAIM

The ornamental design for an inflatable bathtub, as shown and described.

DESCRIPTION

FIG. 1 is a front perspective view of an inflatable bathtub showing my new design;

FIG. 2 is another front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof, and;

FIG. 8 is a bottom view thereof; and,

FIG. 9 is a perspective view of the inflatable bathtub showing the lid in broken lines thereof.

The broken lines in the drawings depict portions of the inflatable bathtub that form no part of the claimed design.

1 Claim, 9 Drawing Sheets(56)
